GLASS GRINDING MACHINE

Paul J. Pilger, North Miami, Fla.

Application March 19, 1952, Serial No. 277,349

1 Claim. (Cl. 51—74)

This invention relates to glass grinding machines and more particularly to a machine for accurately and speedily grinding the longitudinal edges of the glass panels or louvers commonly employed in glass jalousies.

The primary purpose of the invention resides in providing a machine having a continuously moving conveyor mechanism and a plurality of grinding wheels arranged in such manner that parallel groups of glass louvers are continuously conducted along the machine to be engaged by the several grinding wheels to the end that the glass louvers are ground and polished upon their two longitudinal edges prior to discharge from the machine.

A further object of the invention resides in positioning an air blast device that overlies the group of louvers adjacent the discharge end of the machine whereby air is jetted between the several parallel louvers for removing all the water that has accumulated on the louvers during the several grinding stages.

Novel features of the invention and details of construction will be best understood by reference to the accompanying drawings, wherein has been illustrated a preferred example of the device and wherein like characters of reference are employed to denote like parts throughout.

In the drawings:

Figure 1 is a side elevation of a machine constructed in accordance with the invention.

Figure 2 is a fragmentary plan view, frame parts in section and taken upon the line 2—2 of Figure 1.

Figure 3 is a transverse sectional perspective view taken adjacent the take-off end of the machine, illustrating a group of louvers and a drying air nozzle.

Figure 4 is a fragmentary vertical longitudinal section, taken on line 4—4 of Figure 2.

Figure 5 is a fragmentary transverse vertical section, taken on line 5—5 of Figure 4.

Figure 6 is a perspective view of one of the travelling guide carriages hereinafter described and,

Figure 7 is a fragmentary section through one of the grinding wheels.

Referring specifically to the drawings, the machine as illustrated, embodies a plurality of vertical standards 5 formed of angle irons, T-irons or other construction calculated to rigidly support the machine. Parallel and spaced apart angle irons 6 and 7 are horizontally disposed and constitute a trackway that extends for the full length of the machine. Rigidly fixed to the flat upper flange of the angle iron 6, is an inner rail 8 and fixed to the flat upper flange of the angle iron 7, is a preferably, though not necessarily half round rib 9, constituting a rail. The rails 8 and 9 extend for substantially the full length of the angle irons 6 and 7 and constitute a guiding trackway for travelling carriages, indicated as a whole by the numeral 10. These carriages comprise a plurality of spaced apart parallel and vertically disposed rigid plates 11, which receive the end portions of glass louvers 12 between them and guide and hold the louvers upright during their travel through the machine. The carriages com-

2

prise each a transverse bar 13 that rigidly supports the plates 11, with the plates extending both forwardly and rearwardly of the bar and in longitudinal alignment. The innermost and outermost plates 11 are preferably formed integral with the bar 13. A horizontal web 14 projects inwardly from each carriage and this web is provided with a longitudinally extending rib 15 upon its under face and this rib 15 and a downturned flange 16, engage upon opposite sides of the rail 8 and serve to guide the carriages along the track. The outermost plates of the carriages carry elongated studs 17, the under faces of which are preferably grooved at 17a, to engage and ride upon the rail 9. The carriages in predetermined spaced relation are propelled along the track by a continuously travelling conveyor chain 18, that engages an upstanding lug 19 formed upon each web 14. The lug 19 engages within a selected open link of the chain, see Figures 2, 4 and 5. The upper flight of the chain traverses the flat upper flange of the angle iron 6 for substantially the full length of the machine. The chain is driven by any desirable means, such as an electric motor 20, driving through a conventional housed reduction gearing, indicated at 21. The carriages are quickly and easily engaged with the chain by merely lifting the chain, placing the carriages upon the trackway and then dropping the chain to cause one of the links to engage over the lug 19. The carriages obviously, will be properly spaced apart.

The glass louvers are manufactured in varying lengths for a specified width of window opening and louvers of corresponding length are usually grouped for traverse through the machine. By referring to Figure 4, it will be seen that the louvers are of such length with respect to the spacing of two adjacent carriages, that the rear or trailing ends of the louvers are supported and propelled by one carriage, while the forward or leading end of the louvers are supported in the carriage next ahead, that is, the louvers are supported between the plates 11 in a vertical and parallel position throughout their travel through the machine. The louvers are free to shift vertically between the plates 11 and during their travel, their lower edges ride over rollers 22, which are preferably covered by rubber or like cushioning material. During their travel, the louvers ride beneath rubber covered pressure rollers 23, said rollers exerting an adjustable downward pressure under the influence of weights 24. The weights are calculated to exert the proper pressure upon the upper edges of the louvers for maintaining the lower edges in grinding contact with grinding wheels, to be described. The rollers 23 are supported upon transverse shafts 25, which shafts in turn are carried in the outer ends of vertically swinging arms 26. The arms 26 are pivoted at 27 to the vertical standards 5. The arms 26 are adjustably supported in any desirable manner to limit their downward swinging movement, the lowermost position being calculated to properly position the rollers 23 so as to permit the leading edges of the louvers to ride thereunder by forcing the rollers upwardly. Each carriage 10 is provided with transversely disposed cushioning strips 28 and 29, with the strips being grooved, as shown at 30, to have straddling seating engagement over the plates, and the strips 29 and 28 provide cushioning abutments for the end portions of the louvers to prevent chipping the glass as the louvers are propelled through the machine.

As clearly shown in Figure 4, as the louvers travel longitudinally of the machine, under the influence of the carriages being propelled by the chain 18, their lower edges ride over and in grinding contact with rapidly revolving surfaces of grinding wheels 31. These grinding wheels may be grooved, as indicated at 32, in Figure 7 and, the configuration of these grooves determines how much of a rounding off or other bevel shall be imparted

to the longitudinal edges of the louvers. The particular configuration of the grinding wheels is not of the essence of the invention, since a mere flat wheel may be employed in some cases. As shown in Figure 1, there has been illustrated two spaced apart groups of grinding wheels, each group having preferably three grinding wheels with the two groups constituting a first grinding stage and a second grinding stage. The grinding wheels are driven by motors 33, belts 34, pulleys 35 and shafts 36. The grinding wheels rotate in a direction opposed to the travel of the louvers. As clearly shown in Figures 1 and 4, the pressure rollers 23 are located directly over the axial center line of the grinding wheels, which arrangement insures that the edges of the louvers will have full contacting engagement with the grinding surfaces and also insures that the louvers will not be tilted vertically either while entering or leaving the plane of the grinding surface. A pressure roller 23 and associated arm and weight are provided for each grinding wheel. After the louvers pass the first grinding stage, they travel a sufficient distance before entering the second grinding stage to permit an attendant to invert the louvers in the carriages. Thus, in the first grinding stage one longitudinal edge of each louver is ground and in the second grinding stage the other longitudinal edge of each louver is ground. It is not necessary to grind the ends of the louvers because such end portions are engaged in the conventional metallic end brackets commonly employed in louvered closure devices. When the ground louvers reach the take-off end of the machine, they pass beneath an air blast pipe 37, provided with spaced apart air openings, which air blast blows all water, left from the grinding operation and carries with it the major portion of any foreign matter that has adhered to the glass during the grinding and leaves the glass substantially dry and free from accumulated matter for subsequent handling.

It will be apparent, that a very novel and highly efficient machine has been provided that will continuously and completely grind the edges of the glass louvers in a minimum of time. The machine results in a very considerable saving in labor cost, since two and not more than three attendants are capable of controlling the complete operation, one to load the louvers into the carriages at the loading end, one to invert the louvers after passing the first grinding stage and one to take the louvers off at the take-off end. However, the speed of travel is such that the attendant at the take-off end can conveniently invert the louvers. The several grinding wheels are independently driven and the carriages after reaching the take-off end, are removed and transferred back to the loading end manually. The conveyor chain 18 has sufficient slack to permit the positioning of the carriages on

the trackways. Various controls, forming no part of the invention will obviously be employed. As shown in Figures 4 and 2, the spacing of the carriages is determined by the length of the louvers and they are so spaced, that the trailing ends of the louvers have abutting contact with one cushion strip 28, while the leading ends are usually spaced from the cushioning strip 29.

It is to be understood that the invention is not limited to the particular embodiment of the invention shown in the drawings, but that it includes within its purview any changes which fairly fall within either the terms or the spirit of the appended claim.

Having described my invention, what I claim as new and desire to secure by Letters Patent is:

- 15 A supporting and propulsion carriage for use with glass grinding machines of the type that embody an elongated frame having tracks at either side for its full length and with the frame being traversed by an endless conveyor chain and with the frame supporting grinding wheels, the
 20 said carriage comprising a transverse bar having integral vertically arranged and parallel end plates and a plurality of equidistantly spaced and parallel intermediate plates that extend both forwardly and rearwardly of the transverse bar and with the forwardly extending plates being
 25 shorter than the rearwardly extending plates whereby to form sockets for the driving and supporting reception of glass sheets to be ground and with the sheets being supported in an edgewise manner for edgewise engagement with the grinding wheels, one end plate being provided
 30 with an integral horizontally disposed elongated web that is provided with a downwardly opening track groove for traverse engagement with one frame track, the top side of said web being provided with an upstanding lug adjacent its forward end that detachably engages a link of
 35 the conveyor chain and with the web underlying the chain, the opposite end plate being provided with a track engaging stud that traverses the other of said tracks, cushion strips arranged transversely of the carriage and parallel with the bar and with portions thereof disposed between
 40 the several plates whereby to protect the edges of the glass being supported and propelled.
